UNITED STATES PATENT OFFICE

104,491

DESIGN FOR AN ELECTRIC MANICURING MACHINE

Frederick B. Boggs, Springfield, Ohio

Application April 17, 1936, Serial No. 62,180

Term of patent 3½ years

To all whom it may concern:

Be it known that I, Frederick B. Boggs, a citizen of the United States, residing at Springfield, in the county of Clark and State of Ohio, have invented a new, original, and ornamental Design for Electric Manicuring Machine, of which the following is a specification, reference being had to the accompanying drawing, forming part thereof.

Fig. 1 is a top plan view of an electric manicuring machine showing my new design.

Fig. 2 is a perspective view thereof, the drawer being shown in partly open position.

I claim:

The ornamental design for an electric manicuring machine, as shown and described.

FREDERICK B. BOGGS.
